BASE FOR A TABLE LAMP

Harold Bloomfield and Daniel Bloomfield, Glencoe, Ill., assignors to Bloomfield Industries, Inc., Chicago, Ill.

Filed Jan. 29, 1962, Ser. No. 68,541

Term of patent 14 years

(Cl. D48—20)

FIG. 2

FIG. 1 is an elevational view of a base for a table lamp showing our new design, the remaining three sides being the same; and

FIG. 2 shows a top plan view thereof.

The fragmentary portion of a globe is shown in broken lines for illustrative purposes only.

We claim:

The ornamental design for a base for a table lamp, substantially as shown and described.
